UNITED STATES PATENT OFFICE.

WALTER E. TRUFANT, OF WHITMAN, MASSACHUSETTS.

AUTOMOBILE.

SPECIFICATION forming part of Letters Patent No. 696,660, dated April 1, 1902.

Application filed July 5, 1901. Serial No. 67,096. (No model.)

To all whom it may concern:

Be it known that I, WALTER E. TRUFANT, a citizen of the United States, residing at Whitman, county of Plymouth, State of Massachusetts, have invented an Improvement in Automobiles, of which the following description, in connection with the accompanying drawings, is a specification, like letters on the drawings representing like parts.

My invention is an improvement in motors, being particularly intended for application to automobiles, and relating more especially to steam-motors operated by gasoline-fuel and the like. In this class of motors it is necessary to keep the fuel-supply under pressure, this pressure having heretofore been provided by pumping air into the gasoline-tanks or by pumping the gasoline in connection with compressed air. Many disadvantages are recognized as attendant upon the use of air, depending in part upon the mixing tendency which air and gasoline have or the tendency of gasoline to absorb air, the difficulty of pumping air, its liability to leak, the difficulty in handling gasoline without leakage, the difficulty of discovering and preventing the leakages of the air and gasoline, the danger of the resulting gas formed by the air and gasoline, besides various other practical difficulties in the handling and operation of the various forms of gasoline-motors at present in use in auto-vehicles. Accordingly my present invention aims to obviate all the above disadvantages and accomplishes this result by doing away, in the first place, with air, air-pumping in contact with the gasoline, and with substituting therefor a pressure medium to contact with the gasoline which does not unite with the gasoline, is not so liable to leak, and if it does leak is readily visible, introduces no element of danger, is readily pumped, piped, and handled, and by doing away, in the second place, with the presence of gasoline or the gas therefrom in the pipes on the pressure side of the gasoline-tanks, besides reducing the size and simplifying the construction of the apparatus, rendering it almost altogether automatic and largely danger-proof.

The constructional details of my invention and further advantages thereof will be more fully pointed out in the following description,

reference being had to the accompanying drawings, in which I have shown one preferred embodiment of my invention, and the latter will be more particularly defined in the appended claims.

In the drawings, Figure 1 is a side elevation of a motor constructed according to my invention and indicated in position in a usual automobile. Fig. 2 is a top plan view thereof. Figs. 3 and 4 are enlarged vertical sectional views of details to be referred to.

For convenience of illustration I have herein omitted the constructional details of the vehicle-body, running and operating gear, and connected parts, and will confine the present description to those features of the apparatus which embody my invention.

As herein indicated, my invention is embodied in a form of apparatus having two tanks A B, adapted at times to hold gasoline and supply the same to a boiler C, behind which is a water-tank D for supplying water to the boiler and to the tanks A B.

The pressure-transmitting medium which I employ instead of air is water, pumping the same directly into the gasoline, which because of its higher specific gravity remains on top of the water and may readily be held under such pressure as is required for the proper operation of the motor. The water is conducted from the tank through a strainer E by a pipe e, which, as herein shown, is tapped at e' for supplying water to a usual engine-pump f. The water from the pipe e is conducted past a valve e² through an intake-pipe e³ to an automatic pressure-pump g. From the opposite side of the pump g a pipe h leads to a pipe i, the pipe i having interposed at any convenient place in its length an air dome or chamber m, and preferably beyond the same there is a pressure-regulating valve n, connected by a blow-off pipe o back to the pipe e. Although in this embodiment of my invention I have shown the regulator on the pressure side of the pump, yet it will be obvious that if it were placed on the supply side it would operate to reduce the pressure by choking the supply instead of acting as a blow-off or safety valve. At its other end the pipe i is connected by a pipe k to the tanks A B, respectively, being provided with valves k' k², controlling the con-

nexion with these tanks respectively, and also for a purpose to be described having a valve i' interposed between the pipe k and the pump g .

- 5 Gasolene is delivered from the supply tanks to the boiler-burners by a pipe p , containing a usual diaphragm-regulator p' , connected to the tanks by pipe r , containing valves r' r'' . The tanks are also provided 10 with suitable filling-apertures and caps s , air-inlet valves t , and drainage-valves u . On the inlet side of the pump g and preferably from the pipe e^3 an intake-pipe v connects by a pipe v' to the tanks A B, suitable valves v^2 v^3 being interposed similarly as the valves k' k'' , already described. For getting the initial pressure before the engine is started I provide a hand-pump w , preferably connected to the pipe h .
- 15 20 Let it be supposed that the vehicle is in readiness for a long trip, both of the tanks A B being filled with gasolene. The operator, having first opened the valves e^2 , i' , k' , and r' and closed the valves k^2 and r^2 then 25 by means of the hand-pump w raises the water-pressure on the gasolene in the tank A to the point desired, and the engine having been properly started thereby the pump g thereafter automatically maintains the exact 30 pressure required. This is accomplished as follows: The pump g pumps water from the tank E to the tank A, said water being maintained under a uniform pressure by means of the air in the air-dome m , which is more or 35 less compressed in said dome by the pressure of the water in the pipe i , the contained air serving to transmit its elasticity through the water as a conducting medium to the gasolene in the tank A, without, however, 40 any possibility of contact or mixture with the gasolene, and said pressure is maintained within safety limits at any maximum point desired by the pressure-regulator valve n , which may be of any usual type required, a 45 slightly-modified form of a usual pressure valve or regulator being herein indicated in detail in Fig. 4. This valve serves normally to close connection between the pipe i and the pipe o ; but upon passing the maximum- 50 pressure point said valve opens communication between said pipes, thereby at once relieving the pressure and permitting water from the pressure-pipe i to pass back to the water-tank, or, as herein shown, back to the 55 pipe e and thence to said water-tank. By this construction the water can never be pumped beyond safety limits; but whenever the maximum pressure is reached it is automatically discharged back into the tank again, 60 so that if the pump g should continue working when not required it would simply pump water from the tank back into the tank without endangering any of the parts.

The only pipe containing gasolene is the 65 one leading directly from the gasolene-tank to the boiler, the other pipes all being filled with water solely. Water-pumps are easily

operated and are not so difficult to keep in repair and to manage as air or gasolene pumps. Water is not so liable to leak as air or gasolene, and if it does leak it is very readily detected.

70 My apparatus contains only the small amount of air under pressure which is in the air dome or chamber m , and this air is confined to that place, although the benefit of its elasticity and pressure-transmitting power is directly availed of at the tank through the water in the water-pipes i k .

75 One of the most frequent kinds of accidents—viz., air-tank accidents—is thus made impossible, said accidents usually arising from the combination of the gasolene and air capable of forming an explosive gas. Also by using water as a pressure-transmitting medium the pressure is maintained while the vehicle is standing still, whereas in the old air-pressure construction the air would be gradually absorbed by the gasolene, with the result that after a long stand the pressure 80 would be found to be practically all exhausted. Also in the use of air a break in the gasolene-pipe would occasion danger and a loss of the entire supply of gasolene, because in a system 85 wherein air is used to obtain the requisite pressure on the gasolene the air-tank is usually of such a volume as to contain a sufficient quantity of air so that when expanded the air will fill the gasolene-tank, and hence when a break 90 occurred in the gasolene-pipe the compressed air would gradually force the said gasolene out from the break. Where water is used for obtaining pressure, however, the quantity of air under compression in the air-dome is comparatively small, and consequently, even though 95 a leak should occur in the gasolene-pipe, but a comparatively small quantity of gasolene would be wasted before the compressed air in the dome had expanded to atmospheric pressure. As the gasolene is consumed at 100 the boiler the water rises in the tank A until finally the gasolene having all been driven out from said tank, the latter contains nothing but water. Thereupon the valve r' is closed, the valve r^2 is opened for feeding gasolene, the 105 valve k^2 is opened, and the valve k' is closed. The valve e^2 is now closed, and the valve v^2 opened, so that thereafter the operation of the pump g serves to withdraw water from the tank A, whose air-inlet t is open to permit 110 said withdrawal, said water being pumped through the pipes the same as before and delivered into the tank B, the operation being the same as that already described, excepting that in case of overpressure the water is 115 not discharged back into the pipe e to the tank D, but to the pipe v to tank A. By this construction a minimum space for water is required, as the only extra water necessary is enough to fill one of the tanks A, the extra 120 amount of water being carried at the start in the tank D with the water for the boiler, and when withdrawn from said main tank into the tank A it is then pumped from that tank 125 130

into the tank B until both of the gasoline-tanks are emptied of gasoline.

A further advantage of my construction is that it is readily adapted for use in winter, 5 when one of the tanks A B may be provided with a non-freezing liquid and the other tank used for gasoline, said liquid being pumped into the gasoline in the same manner as has been described for water.

10 My apparatus is also readily convertible to various other applications simply by closing certain of the valves and opening others.

It will be understood that in practice the pipes are more compactly arranged, being 15 herein shown separated and placed in different vertical planes for clearness of illustration and description.

I have endeavored to reduce all the parts to extreme simplicity. For example, the 20 strainer comprises simply a shell e^6 , cap e^6 , and wire screen e^8 , which is slipped inside the shell and maintained in place frictionally or by the cap e^6 . When it is to be emptied, it is simply taken out, emptied of its sediment, 25 and shoved back in place without requiring special care or manipulation.

The pressure-regulator n comprises a chamber n' , containing a diaphragm n^2 , normally held down by a spring n^3 , all these parts being 30 of usual construction, excepting that the diaphragm carries a valve n^4 , operating to open the water-passage upon upward movement of the diaphragm.

The engine and general features in connection therewith may be of any usual kind, and accordingly I have largely omitted the same, having merely indicated in dotted lines in Fig. 1 a gear x and its crank x' , connected at x^2 to a walking beam or lever x^3 , which operates 35 the pump g , and in Fig. 2 I have indicated a double engine at $X X'$.

I wish it understood that I am not limited otherwise than as expressed in the claims and that very many changes and substitutions in 40 constructional details and arrangement of parts may be had within the spirit and scope of my invention, and while I have mentioned "gasoline" I wish it understood that by that term I mean to include any of the liquid fuels 45 which are used or might conveniently be used for the purpose.

Having fully described my invention, what I claim as new, and desire to secure by Letters Patent, is—

55 1. In an apparatus of the kind described, a source of gasoline-supply for heating a boiler, a source of water-supply, a pipe connecting the two, means for forcing said water to said gasoline under pressure, an air-dome connected to said water-pipe on the pressure side of said pressure means, and a pressure-regulator for preventing the pressure exceeding a given maximum.

2. In an apparatus of the kind described, a 60 gasoline-tank, a pipe adapted to connect said tank to a boiler, a water-tank, a pipe connecting said water-tank to the gasoline-tank,

a pressure-pump for forcing the water under pressure to said gasoline-tank, a pressure-regulator connected with said water-pipe on 70 the pressure side of said pump, and a blow-off connection from said pressure-regulator to the intake side of said pump.

3. In an apparatus of the kind described, a water-tank, a plurality of gasoline-tanks for 75 supplying gasoline for heating a boiler, pipe connections between said several tanks, means for forcing water under pressure to one of said gasoline-tanks either from said water-tank, or from the other gasoline-tank as may 80 be desired.

4. In an apparatus of the kind described, a water-tank, a plurality of gasoline-tanks for supplying gasoline for heating a boiler, pipe connections between said several tanks, and 85 means for forcing water under pressure to either of said gasoline-tanks from said water-tank, or to one of said gasoline-tanks from the other as desired.

5. In an apparatus of the kind described, a 90 water-tank, a plurality of gasoline-tanks for supplying gasoline for heating a boiler, pipe connections between said several tanks, means for forcing water to one of said gasoline-tanks from said water-tank, means for 95 cutting off said water-supply and thereafter withdrawing the water previously forced to said gasoline-tank and forcing the same under pressure to another gasoline-tank.

6. In an apparatus of the kind described, a 100 water-tank, a plurality of gasoline-tanks for supplying gasoline for heating a boiler, pipe connections between said several tanks, a pump for forcing water to one of said gasoline-tanks from said water-tank, means for 105 cutting off said water-supply and thereafter withdrawing the water previously forced to said gasoline-tank and forcing the same under pressure to another gasoline-tank, and a pressure-regulator having a blow-off connection for discharging into either source of water-supply as the case may be.

7. In an apparatus of the kind described, a 110 plurality of tanks adapted to contain either gasoline for heating a boiler or water for 115 communicating pressure to the gasoline, water-pipes connecting said tanks, and a pump for drawing water from one tank and delivering it under pressure to the other tank.

8. In an apparatus of the kind described, a 120 plurality of tanks, adapted to contain either gasoline for heating a boiler or water for communicating pressure to the gasoline, water-pipes connecting said tanks, and a pump for drawing water from either of said tanks 125 and delivering it under pressure to the other tank.

9. In an apparatus of the kind described, a 130 plurality of tanks, one for containing pressure-transmitting fluid and the other for containing gasoline, a gasoline-pipe for delivering gasoline to a boiler, two sets of connecting-pipes between said tanks, said two sets of pipes being connected together and hav-

ing a pressure-pump interposed therein for transmitting pressure through said pipes, and valves on each side of said two connections for governing the communication of said pressure-pump with one or another of said tanks.

5 In testimony whereof I have signed my

name to this specification in the presence of two subscribing witnesses.

WALTER E. TRUFANT.
